UNITED STATES PATENT OFFICE.

BENJAMIN F. SILLIMAN, OF CLEVELAND, OHIO.

REGULATING APPARATUS FOR STEAM-GENERATORS.

1,015,848.

Specification of Letters Patent.

Patented Jan. 30, 1912.

Application filed April 20, 1908. Serial No. 428,043.

To all whom it may concern:

Be it known that I, BENJAMIN F. SILLIMAN, a citizen of the United States, resident of Cleveland, county of Cuyahoga, and State of Ohio, have invented a new and useful Improvement in Regulating Apparatus for Steam-Generators, of which the following is a specification, the principle of the invention being herein explained and the best mode in which I have contemplated applying that principle, so as to distinguish it from other inventions.

The present invention relating, as indicated, to the regulation of steam generators, has more particular regard to such regulation in connection with generators of the so called flasher type, which are largely used in connection with automobiles, launches, and the like. In such generators, as is well known, the water is entered at an upper coil and the steam delivered from a lower coil, which is the hottest part of the boiler, the fuel being concurrently supplied to the burner in properly correlated quantity to that of the water so as to provide steam at the desired temperature and pressure. Usually this type of generator is employed at high pressures, the steam being superheated, and this fact aside from the general principles of operation involved therein, renders such generators more or less unreliable in operation as well as short lived, considerable experience and skill being furthermore required in their successful use. For this reason some system of regulation more or less automatic in character has been regarded as necessary in order to enable the generator to meet the exigencies of use with the frequently changing demand for power imposed by the conditions of such use.

The object of the present invention is the provision of a more perfect and satisfactory type of automatic regulating apparatus for use in the connection just referred to. To this end said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings: Figure 1 rep-

resents in more or less diagrammatic fashion 55 a steam generator and an arrangement of apparatus in connection therewith embodying the principle of operation of my invention; Figs. 2, 3, and 4, represent, in section, various details of such apparatus. 60

Referring to Fig. 1 and the general arrangement of apparatus there illustrated, the generator will be seen to comprise a tubular boiler A, the specific construction of which is a matter of indifference so far 65 as the present invention is concerned; any one of the several prevailing types of generator, in other words, will prove equally susceptible to regulation by the apparatus herein shown. Water is supplied to the 70 generator through a feed pipe a and the steam is led therefrom to the engine (not shown) through a steam pipe a'. The heating means necessarily provided in connection with the generator A, comprise a 75 burner A', shown in conventional form, to which the fuel is led through a supply pipe a''. Such fuel, whether gaseous or liquid, is designed to be supplied from a tank or the like (not shown) under suitable con- 80 stant pressure to force the same to the burner, where it is ignited. The supply of water to the generator, on the other hand, is furnished by a pump B, shown as a double-cylinder pump for reasons presently 85 to be explained, that is connected with suitable driving means, preferably the engine operated by the generator. Pump B is de- 90 signed to be regulated independently of the apparatus herein shown and described so 95 as to operate responsively to the supply of water admitted thereto by the regulating device C (constituting a part of the present apparatus), such pump being located between the last-named regulating device 100 and the generator. Any suitable form of governor may be thus employed to control the pump. The particular location of the pump, however, is immaterial since, if de- 105 sired, regulating device C may be located between the pump and the generator, and the excess of water forced by the pump be diverted back again to the tank. The former arrangement, however, is the more desirable, since unnecessary waste of power is thereby avoided. Turning then to the regu- 110 lating apparatus proper, such apparatus will be seen to comprise three separate de-

vices, one, C, of which, for controlling the supply of water to the pump, has already been referred to. The second device A² is provided in connection with the fuel supply pipe a² for regulating the amount of fuel furnished thereby, while the third B' adjoins one cylinder of the pump B described above, coöperating with said cylinder to render the same inoperative on occasion. Each of these three devices is actuated by pressure fluid supplied from a common source (not shown) through suitable ducts or passages d. Each of these devices will now be examined more particularly with a view of ascertaining the character of the operation in the devices effected by such pressure fluid and the mode of regulating the supply of such fluid to vary such operation.

- 20 Regulating device C, Fig. 4, for controlling the supply of water to the pump, comprises simply a reciprocable piston valve c, the larger face of which is adapted to be exposed to the pressure fluid in a diaphragm chamber c'. Admission of such fluid to this chamber is controlled by a second, or pilot, valve c² operated by the pressure in a diaphragm chamber c³ that has connection with the steam pipe a leading from the generator. 25 The opposite side of such last named valve being exposed simultaneously to the air pressure in a chamber c⁴, a differential effect will be had and the sensitiveness of action on the part of the pilot valve thus increased. Com- 30 pression springs c⁵ c⁶ are provided in connection with valves c and c², respectively, being adapted to normally hold the same in closed position, and a small vent opening c⁷ in the casing of chamber c' serves to relieve 35 the pressure in such chamber immediately upon the supply of pressure fluid being cut off by valve c².

The device A², regulating the supply of fuel to the burner, is shown in Fig. 2 and 45 comprises in effect a needle valve a⁴ that is normally maintained in closed position by a spring a⁵, while actuation thereof to open the supply is had by admission of pressure fluid into diaphragm chamber a⁶, the dia- 50 phragm, forming one wall of this chamber, being connected with the valve in question. The regulating device B', connected with the one cylinder of pump B includes a reciprocable plunger b² adapted to hold off its seat 55 the check valve b³ located in the inlet pipe b⁴ of such cylinder. This plunger is movable by a flexible diaphragm b⁵ in a chamber b⁶ exposed to the same pressure fluid as the other previously described regulating de- 60 vices. Such pressure fluid, when thus allowed to act, obviously renders the pump cylinder in question inoperative, the pressure in the water supply main a being assumed to be less than that against which the 65 water must be forced in order to cause it to

enter the generator. Upon the pressure being lowered in diaphragm chamber b⁶, a spring b⁷ is effective to retract plunger b², thus allowing the check valve to seat itself again whereupon the pump cylinder affected 70 operates normally. A vent opening d² is provided in the pressure fluid duct d that leads to the device B', adjustment of the amount of the leak permitted therethrough being had by means of a set screw d³, see 75 Fig. 1.

The supply of pressure fluid to the fuel regulating and pump regulating devices, A², B', respectively, is simultaneously had by a thermostatic device A³ in connection 80 with the generator. While such device may take on various forms, it preferably consists of the lower terminal portion of the generator coil a⁸ which is straightened out and disposed transversely of the generator shell, 85 as shown. The inner end of such straightened section being secured to the shell, the other end will obviously have a slight movement as the tube section in question expands and contracts in response to changes of tem- 90 perature in the generator. Whether such changes be due to changes in the temperature of the steam vapor within the tube, or by reason of the undue heating effect of the generator, which is located in direct prox- 95 imity thereto, will make no difference so far as the operation of this thermostat is concerned. Connected with the outer, free, or movable, end a⁹ of the tube section constituting the thermostat is a valve a¹⁰ fitted in 100 a valve-casing D interposed in the line of pressure fluid supply between the source of pressure supply and the two regulating devices A² B' to which reference has been last made, expansion of the tube being effective 105 to close the valve and thus shut off the supply of pressure fluid to both devices.

Pressure-fluid supply pipe is furthermore provided with a general control valve d⁴ whereby the pressure may simultaneously be 110 cut off from the several regulating devices A², B' and C, and the latter allowed to assume their normal positions, namely device A² will close off the fuel supply, device B' will permit its valve b³ to seat, thus restoring the corresponding pump cylinder to its operative condition, and regulator C will open wide the supply of liquid to the generator. All this, it will be evident, is done quite irrespective of the particular condition of any such regulating devices by reason of the steam-pressure control in the one case, or the thermostatic control in the case of the two others. In addition I provide for operation of general pressure control valve 115 d⁴ conjointly with the operation of throttle valve a¹⁰ in steam delivery pipe a by connecting levers d⁵ a¹¹, mounted on the respective valves, with a common actuating rod E. The results just noted as occurring upon the 120

closing valve d^4 are accordingly automatically jointed to and made coincident with the closing of throttle valve a^{10} .

Having thus described the structure of the several parts of my improved regulating system, and necessarily at the same time the operation of such parts it merely remains to indicate briefly the manner in which they coöperate in the production of the desired result, viz. the generation of steam in proper amount and under desired pressure to supply the varying needs of the motor. Assuming then the latter to be at a standstill the throttle and general pressure control valves will be simultaneously opened by means of rod E. The admission of pressure fluid to duct d will not alter the status of regulator C, but will open full the fuel supply, as also throw out, or render inoperative, the pump cylinder with which regulator A² is associated. The predetermined amount of water fed by the single pump cylinder, that is in operation, is promptly converted into steam since the burner is operating to give a maximum heating effect. This condition of parts continues as long as the demand for power is equal to that which is provided by the vaporization of the predetermined supply of water. This, it is designed, will be sufficient to supply the maximum normal demand that may be placed upon the generator. Accordingly as the pressure in the generator mounts up, owing to less power being required than such maximum, regulator C is affected, and the supply of water cut down. Simultaneously with such increase in steam pressure, and still more upon decrease in water supply, thermostat A is actuated by the unabsorbed heat of the burner to decrease the supply of fuel. Should the heat in the generator still be too great the further expansion of the thermostat, aside from more completely, or entirely, closing off the fuel supply, will be effective to throw into operation the second pump cylinder thereby increasing the supply of liquid to the boiler beyond the predetermined amount corresponding with the contemporaneous demand for power. By reason of the unique construction of thermostat utilized in my regulating system, this additional supply of water will also occur whenever for any other reason the heating of the boiler becomes abnormal. Thus it operates when the lower portion of the coil becomes dry just as readily as when the steam contained within the coil reaches an immoderate temperature.

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention:—

1. In apparatus of the character described, the combination of a generator; heating means coöperative therewith; means for regulating the supply of liquid to said generator and of fuel to said heating means, respectively; fluid-pressure actuated means for operating each of said regulating means; means, operating automatically according to the demand for power upon said generator, for controlling the supply of pressure fluid to said fluid-pressure actuated means; and means adapted simultaneously to throttle said generator and control such supply of pressure fluid.

2. In apparatus of the class described, the combination of a generator; heating means coöperative therewith; means for regulating the supply of fuel to said heating means, said regulating means normally tending to cut off such supply; fluid-pressure means adapted to open such supply; and thermostatic means in connection with said generator for controlling the supply of pressure fluid to said last-named means.

3. In apparatus of the class described, the combination of a flasher type generator; heating means coöperative therewith; means for regulating the supply of fuel to said heating means, said regulating means normally tending to cut off such supply; fluid-pressure means adapted to open such supply; and thermostatic means, consisting of a portion of the coil of said generator, for controlling the supply of pressure fluid to said last-named means.

4. In apparatus of the class described, the combination of a flasher type generator; heating means coöperative therewith; means for regulating the supply of fuel to said heating means, said regulating means normally tending to cut off such supply; fluid-pressure means adapted to open such supply; and thermostatic means, consisting of the lower terminal portion of the coil of said generator, for controlling the supply of pressure fluid to said last-named means.

5. In apparatus of the class described, the combination of a generator; heating means coöperative therewith; means for controlling the supply of fuel to said heating means, said controlling means normally tending to cut off such supply; fluid-pressure means adapted to open such supply; and means adapted simultaneously to throttle said generator and control such supply of pressure-fluid.

6. In apparatus of the class described, the combination of a generator; heating means coöperative therewith; means for controlling the supply of fuel to said heating means, said controlling means normally tending to cut off such supply; fluid-pressure means adapted to open such supply;

thermostatic means in connection with said generator for controlling the supply of pressure-fluid to said last-named means; and means adapted simultaneously to throttle 5 said generator and control such supply of pressure-fluid.

7. In apparatus of the class described, the combination of a generator; heating means coöperative therewith; means for regulating 10 the supply of liquid to said generator and of fuel to said heating means, respectively, the fuel-supply regulating means normally tending to cut-off such supply; fluid-pressure actuated means for operating each of 15 said regulating means, said fluid-pressure actuated means being adapted, in the case of the fuel-supply regulating means, to open the supply; and means, operating automatically according to the demand for power 20 upon said generator, for controlling the supply of pressure fluid to said fluid-pressure actuated means, respectively.

8. In apparatus of the class described, the combination of a generator; heating means 25 coöperating therewith; means for regulating the supply of liquid to said generator and of fuel to said heating means, respectively, the liquid-supply regulating means normally tending to open, and the 30 fuel-supply regulating means to close, the corresponding supply; fluid-pressure actuated means adapted to open said fuel supply and close said liquid supply, respectively; and means, respectively affected by the tem- 35 perature and pressure in said generator, for controlling the supply of pressure fluid to said fluid-actuated means, respectively.

9. In apparatus of the class described, the combination of a flasher type generator; 40 heating means coöperative therewith; means for regulating the supply of liquid to said generator and of fuel to said heating means, respectively, the liquid-supply regulating means normally tending to open, and the 45 fuel-supply regulating means to close, the corresponding supply; fluid-pressure actuated means adapted to open said fuel supply, and close said liquid supply, respectively; thermostatic means, consisting of a 50 portion of the coil of said generator, for controlling the supply of pressure-fluid to the pressure actuated means connected with the fuel-supply regulating means; and a device, affected by the pressure in said generator, for controlling the supply of such fluid to the pressure actuated means connected 55 with the liquid-supply regulating means.

10. In apparatus of the class described, the combination of a generator; heating means 60 coöperative therewith; means adapted to supply a constant amount of liquid to said generator; other means adapted to increase the amount of liquid thus supplied, said last-named means being normally inoperative; and thermostatic means in con- 65

nnection with said generator adapted to render said last-named means operative.

11. In apparatus of the class described, the combination of a generator; heating means coöperative therewith; means adapted 70 to supply a constant amount of liquid to said generator; other means adapted to increase the amount of liquid thus supplied; fluid-pressure actuated means adapted to render said last-named means inoperative; and thermostatic means in connection with said generator adapted to cut off the supply of pressure fluid from said fluid-pressure actuated means.

12. In apparatus of the class described, 80 the combination of a generator; heating means coöperative therewith; two pumps for supplying liquid to said generator; means, affected by the pressure in said generator, for controlling the amount of liquid 85 thus supplied by both said pumps; independent means, affected by the temperature in said generator, for controlling the amount supplied by one of said pumps.

13. In apparatus of the class described, 90 the combination of a generator; heating means coöperative therewith; two pumps for supplying liquid to said generator; means, affected by the pressure in said generator, for controlling the amount of liquid 95 thus supplied by both said pumps; fluid pressure actuated means adapted to normally render one of said pumps inoperative; and thermostatic means in connection with said generator adapted to cut off the supply of 100 pressure fluid from said fluid-pressure actuated means, and thereby render said pump operative.

14. In apparatus of the class described, 105 the combination of a generator; heating means coöperative therewith; two pumps for supplying liquid to said generator; means adapted to regulate the amount of liquid thus supplied by both said pumps, 110 said means leaving such supply normally open; fluid-pressure actuated means adapted to close said regulating means; other fluid-pressure actuated means adapted to normally render one of said pumps inoperative; means adapted upon predetermined pressure 115 in said generator to open the supply of pressure fluid to said first-named fluid-pressure actuated means; and thermostatic means in connection with said generator adapted to cut off the supply of such fluid to said last-named fluid-pressure actuated means.

15. In apparatus of the class described, 120 the combination of a generator; heating means coöperative therewith; means adapted 125 to supply a constant amount of liquid to said generator; other means adapted to increase the amount of liquid thus supplied; fluid-pressure actuated means adapted to render said last-named means inoperative; thermostatic means in connection with said 130

generator adapted to cut off the supply of pressure-fluid from said fluid-actuated means; and means adapted independently to cut off the supply of such fluid and to 5 simultaneously throttle said generator.

16. In apparatus of the class described, the combination of a generator; heating means coöperative therewith; means adapted to supply a constant amount of liquid to 10 said generator; and means, operating automatically according to the demand for power upon said generator, respectively adapted to increase the amount of liquid thus supplied and to cut off the supply of fuel to 15 said generator.

17. In apparatus of the class described, the combination of a generator; heating means coöperative therewith; means adapted to increase the amount of liquid thus supplied, said last-named means being normally inoperative; thermostatic means in 20 connection with said generator adapted to render said last-named means operative; and means, similarly controlled by said 25 thermostatic means, adapted to cut off the supply of fuel to said heating means.

18. In apparatus of the class described, the combination of a generator; heating means coöperative therewith; means adapted to supply a constant amount of liquid to 30 said generator; fluid-pressure actuated means respectively adapted to increase the amount of liquid thus supplied and to cut off the supply of fuel to said heating means; and thermostatic means in connection with 35 said generator for controlling the supply of pressure-fluid to said fluid-pressure actuated means.

19. In apparatus of the class described, 40 the combination of a generator; heating means coöperative therewith; means adapted to increase the amount of liquid thus supplied, said last-named means being normally inoperative; fluid-pressure actuated means 45 respectively adapted to render said last-named means operative and to cut off the supply of fuel to said heating means; and thermostatic means in connection with said generator for controlling the supply of pressure-fluid to 50 said fluid-pressure actuated means.

20. In apparatus of the class described, the combination of a generator; heating means coöperative therewith; two pumps 55 for supplying liquid to said generator; means, affected by the pressure in said generator, for controlling the amount of liquid supplied by both said pumps; independent means, affected by the temperature in said 60 generator, adapted to control the amount of liquid supplied by one of said pumps; and other means, likewise affected by the temperature in said generator, adapted to regulate the supply of fuel to said heating means.

21. In apparatus of the class described,

the combination of a generator; heating means coöperative therewith; two pumps for supplying liquid to said generator; means, affected by the pressure in said generator, for controlling the amount of liquid 70 supplied by both said pumps; fluid-pressure actuated means respectively adapted to normally render one of said pumps inoperative and to cut off the supply of fuel to said heating means; and thermostatic 75 means in connection with said generator for controlling the supply of pressure-fluid to said fluid-pressure actuated means.

22. In apparatus of the class described, the combination of a generator; heating 80 means coöperative therewith; two pumps for supplying liquid to said generator; means adapted to regulate the amount of liquid thus supplied by both said pumps, said means leaving such supply normally 85 open; fluid-pressure actuated means adapted to close said regulating means; other means respectively adapted to normally render one of said pumps operative and to cut off the supply of fuel to said heating 90 means, said means being actuated by fluid-pressure to render said pump inoperative and to open such fuel supply; means adapted upon predetermined pressure in said generator to open the supply of pressure-fluid 95 to said first-named fluid-pressure actuated means; and thermostatic means in connection with said generator adapted to cut off the supply of such fluid to said other fluid-pressure actuated means. 100

23. In apparatus of the class described, the combination of a generator; heating means coöperative therewith; two pumps for supplying liquid to said generator; means adapted to regulate the amount of liquid thus supplied by both said pumps, said means leaving such supply normally 105 open; fluid-pressure actuated means adapted to close said regulating means; other means respectively adapted to normally render one of said pumps operative and to cut off the supply of fuel to said heating means, said means being actuated by fluid-pressure to render said pump inoperative and to open such fuel supply; means adapted upon 110 predetermined pressure in said generator to open the supply of pressure-fluid to said first-named fluid-pressure actuated means; and thermostatic means, consisting of a portion of the coil generator, adapted upon 115 a predetermined temperature in the latter to cut off the supply of such fluid to said other fluid-pressure actuated means.

24. In apparatus of the class described, the combination of a generator; heating 125 means coöperative therewith; two pumps for supplying liquid to said generator; means adapted to regulate the amount of liquid thus supplied by both said pumps, said means leaving such supply normally 130

open; fluid-pressure actuated means adapted to close said regulating means; other means respectively adapted to normally render one of said pumps operative and to cut off the supply of fuel to said heating means, said means being actuated by fluid-pressure to render said pump inoperative and to open such fuel supply; means adapted upon predetermined pressure in said generator to 10 open the supply of pressure-fluid to said first-named fluid-pressure actuated means; and thermostatic means, consisting of the lower terminal coil of said generator, adapted upon a predetermined temperature in the 15 latter to cut off the supply of such fluid to said other fluid-pressure actuated means.

25. In apparatus of the class described, the combination of a generator; heating means coöperative therewith; two pumps 20 for supplying liquid to said generator; means adapted to regulate the amount of liquid thus supplied by both said pumps, said means leaving such supply normally open; fluid-pressure actuated means adapted

to close said regulating means; other means 25 respectively adapted to normally render one of said pumps operative and to cut off the supply of fuel to said heating means, said means being actuated by fluid-pressure to render said pump inoperative and to open 30 such fuel supply; means adapted upon predetermined pressure in said generator to open the supply of pressure-fluid to said first-named fluid-pressure actuated means; thermostatic means in connection with said 35 generator adapted to cut off the supply of such fluid to said other fluid-pressure actuated means; and means adapted, independently of aforesaid means, to cut off the supply of such fluid and to simultaneously 40 throttle said generator.

Signed by me, this 17th day of April, 1908.

BENJAMIN F. SILLIMAN.
